UNITED STATES PATENT OFFICE.

ALONZO IRVEN THOMAS, OF EUREKA, CALIFORNIA.

SAWDUST AND LIKE FINE-FUEL FURNACE.

Application filed January 7, 1924. Serial No. 684,759.

To all whom it may concern:

Be it known that I, ALONZO I. THOMAS, a citizen of the United States, residing at Eureka, in the county of Humboldt and

5 State of California, have invented certain new and useful Improvements in Sawdust and like Fine-Fuel Furnaces, of which the following is a specification, reference being had therein to the accompanying drawings.

10 This invention relates to a furnace primarily intended for burning saw dust and other comminuted wood but also adapted to burn fine and low grade fuels of various kinds.

15 One of the largest items of expense in connection with furnaces of the character indicated is that of burned out grate bars. Due to the closely packed nature of the fuel it is difficult to get air through grate bars of 20 ordinary construction, particularly if the grate bars be close enough together to prevent the fine fuel from falling through. The result is that not only is it difficult to maintain sufficient air supply to support combustion but, in addition, the grate bars rapidly burn out or become so warped as to render them useless.

In the Patent No. 1,410,141 issued to me on the 21st day of March 1922 I have disclosed a construction wherein the saw dust or other fine fuel is burned upon what is substantially a solid bottom, air being forced into the fuel from suitable conduits.

25 In my copending application Serial Number 676,451, filed November 22, 1923, I have disclosed a furnace of the same general character as that illustrated in my patent but wherein certain economies of construction are brought about and wherein the air discharging nozzles are bodily removable for ready replacement when they are burned out.

30 The present invention comprises a furnace of the same general character as those shown in the patent and application above referred to but wherein the parts are so arranged that nothing about the furnace is likely to burn out. But, if it should burn out, the burned out part may be readily replaced at a very small cost.

35 The means by which these objects are achieved are disclosed in the accompanying drawings wherein—

40 Fig. 1 is a longitudinal sectional view through a part of a furnace illustrating a preferred form of the invention;

Fig. 2 is a transverse sectional view through the furnace of Fig. 1;

Fig. 3 is a longitudinal sectional view illustrating a modified form of the invention.

45 Fig. 4 is a transverse sectional view through the form of furnace illustrated in Fig. 2;

Fig. 5 illustrates a housing of fire-brick or like refractory material having open sides 65 adapted to receive tuyère irons hereinafter described;

Fig. 6 is a perspective view of a fire-brick hereinafter described; and

Fig. 7 is a perspective view of a metallic plate constituting a tuyère iron and adapted for use in the furnace illustrated in Figs. 3 and 4.

50 Like numerals designate corresponding parts in all of the figures of the drawings.

55 In both forms of the invention, the furnace comprises a hearth or base 5 which may be of concrete or any other suitable material. Formed in this hearth are a plurality of longitudinally extending ducts. There 60 may be any number of these ducts and they may be located in varying positions with respect to the side walls of the furnace. For purposes of illustration I have illustrated two inner ducts 6 and two outer ducts 7. The 65 two outer ducts are connected by a transverse cross-duct 8 which is supplied with air through a conduit 9 and the two inner ducts are supplied with air through a conduit 10 which leads to a well 11 which is 70 common to both of the inner ducts. Where the base 5 is made of a cheap and comparatively low grade concrete, I may, if desired, face its upper surface with a highly heat resisting fire-brick, indicated at 12 75 though I may dispense with this fire-brick and make the base 5 of any suitable heat resisting cement.

80 In the form of the invention illustrated in Figs. 1 and 2 the furnace structure comprises the specially made refractory brick illustrated in Fig. 6. These bricks are placed together end to end and have a plurality of air discharge ports 13 formed in their side walls 14. I have illustrated the 85 tops of these brick as being inclined downwardly upon opposite sides of the central line of said blocks. This is of utility in that it tends to cause the saw dust or material to move down toward the jets of air 90

being discharged from the ports as the fuel is consumed.

By referring to Fig. 2 it will be seen that the material of the base upon which the fire-brick is supported is notched out as indicated at 15 along the edges of the ducts 7 and these notched out portions receive the lower edges of the bricks 16, hereinbefore described. Thus these notched out portions 10 constitute guides by which the bricks are caused to lie in accurate alignment with each other and without the necessity for other means for holding them in place.

In the form of the invention illustrated in Figs. 3, 4, 5, and 7 the ducts 7 are spanned by longitudinally extending housings 17 the sides of which are open as indicated at 18, except that at suitable intervals supporting and strengthening ribs 19 are provided. 20 This leaves comparatively long and wide openings in which the tuyère irons, indicated in Fig. 7 and numbered 20, are placed. These tuyère irons have discharge ports 21 formed in them through which air is discharged from the interior of the ducts 7 outwardly through said ports and into the pile of saw dust or like material. Any suitable means may be employed for holding the tuyère irons in place. As one means 30 of accomplishing this result, I have illustrated angle irons 22 which lie outwardly of the tuyère irons or plate 20 and which angle irons have openings formed in them corresponding with the port 21. The 35 tuyère irons or plates illustrated in Fig. 7 may be made in varying lengths. They may be made quite short and there may be a large number of them or they may be made longer and of a correspondingly less number. Since they are in large measure protected by being seated within the refractory housing 17, it follows that they will not readily burn out and if any of them should burn out it is a simple matter to replace the burned out element or elements. 45 The same thing is true with respect to the bricks illustrated in Fig. 6. Any one of these bricks may be replaced without disturbing any of the others, it being only necessary to lift the burned out brick from its place and to set another brick in its place. 50 In Fig. 5 I have illustrated upstanding portions 12^a constituting a limiting means for limiting the inward movement of the 55 plate of Fig. 7 at the lower edge of said

plate and I have indicated downwardly extending ribs 17^a for limiting inward movement of said plate at the upper edge of the said plate.

It is to be understood that the invention 60 is not limited to the precise construction set forth but that it includes within its purview whatever changes fairly come within either the terms or the spirit of the appended claims.

Having described my invention what I claim is:

1. A furnace of the character described comprising a masonry base having a plurality of open ducts formed therein, means for supplying air to said ducts from the exterior of the furnace, and refractory housings of inverted U shape in cross section having laterally open ports in their side walls which housings span said ducts and are continuous throughout the length of said ducts, the edges of said housings being seated along the edges of said ducts.

2. A furnace of the character described comprising a base having a plurality of open top ducts formed therein, means for supplying air to said ducts from the exterior of the furnace and a plurality of hollow fire-brick of inverted U shape spanning said ducts and continuous throughout the length thereof, said bricks being placed together end to end to constitute housings over said ducts, said bricks having laterally open ports in their side walls.

3. A structure as recited in claim 2 90 wherein said brick have inclined tops.

4. A structure as recited in claim 2 wherein in the base is recessed along said ducts for the reception of the lower edges of said brick.

5. A furnace of the character described comprising a base of masonry having a plurality of open top ducts formed therein, means for supplying air to said ducts from the exterior of said base, housings disposed over said ducts and extending longitudinally thereof in an unbroken line, said housings being formed of refractory material and having openings formed in their side walls and metallic tuyère plates seated in said openings.

In testimony whereof I hereunto affix my signature.

ALONZO IRVEN THOMAS.
